UNITED STATES PATENT OFFICE

99,368

DESIGN FOR A CHILD'S GARMENT

Margaret S. Raimer, Danville, Ill.

Application January 28, 1935, Serial No. 55,092

Term of patent 14 years

To all whom it may concern:

Be it known that I, Margaret S. Raimer, a citizen of the United States, residing at Danville, in the county of Vermilion and State of Illinois, have invented a new, original, and ornamental Design for a Child's Garment, of which the following is a specification, reference being had to the accompanying drawing. The figure in the drawing is a front view of a garment containing my new and ornamental design.

The dominant or characterizing feature of my design resides in a conventionalized representation of a quadruped applied to or forming a part of the front of a garment of a type such as shown. The back of the garment is of conventional form.

I claim:

The ornamental design for a child's garment substantially as shown and described.

MARGARET S. RAIMER.
